UNITED STATES PATENT OFFICE.

GEORGE P. ANSTISS, OF OAK PARK, ILLINOIS, ASSIGNOR TO G. S. BLAKESLEE & CO., OF CICERO, ILLINOIS, A CORPORATION OF ILLINOIS.

WASHING MACHINE.

Application filed April 23, 1927. Serial No. 185,938.

My invention relates to machines for washing dishes and other articles, and has particularly to do with washing machines of the type in which the articles to be washed, while contained in a basket or other suitable receptacle, are moved through the machine past means, such as a paddle wheel or wheels, that serves to throw water forcibly against the articles. In its broadest aspect my invention is not concerned with the particular means employed for effecting the washing, although more specifically considered it includes improved means by which this is accomplished. The primary feature of my invention which I believe to be generically new is the incorporation in a washing machine of the type referred to of means for advancing the articles to be washed through the machine intermittently, or in other words, by stages, the propelling means being normally inactive, and being arranged to be set in operation during a predetermined interval after which it will stop and remain inactive until it is again started. The starting of such advancing means is under the control of the operator and is preferably accomplished by the introduction of a basket into the machine, although it may be accomplished by a separate manual operation. In either case, however, it automatically stops after advancing the articles to a predetermined extent. In connection with this operation of the advancing means, my invention also includes means for automatically spraying the articles as they pass out of the machine, so that they are rinsed and dried after the washing operation, the spraying water being supplied only while the washed articles are moving out of the machine, so that it is not wasted. In addition to these features, my invention also includes improved means for moving the baskets through the machine, by which danger of damage in case the progress of the baskets is interfered with, is avoided, and also certain other improvements of a more specific character which will be hereinafter pointed out.

In the accompanying drawings I have chosen to illustrate my invention as incorporated in a dish washing machine comprising a casing that encloses a tank over which the baskets containing the dishes are moved, and a compartment at one side of the casing in which is contained a rotating paddle wheel, the blades of which take up the water from the tank and throw it forcibly against the

contents of the basket, the baskets being moved through the machine past the paddle wheel compartment by an endless conveyor, the upper flight of which travels above the level of the water in the tank. It should be understood, however, that generically considered my invention is not limited to the particular arrangement shown and described, as it may be applied to washing machines in which the washing is accomplished in other ways, as, for example, by the use of jets through which the water is discharged under pressure, such as are well known to those familiar with the art.

In the accompanying drawings,—

Fig. 1 is a plan view of my improved washing machine, part of the top of the housing being broken away to expose some of the operating parts enclosed therein;

Fig. 2 is a perspective view of the ratchet wheel that forms part of the mechanism by which the baskets are advanced through the machine;

Fig. 3 is also a perspective view showing other parts of the advancing mechanism and of the means for controlling the operation of the rinsing devices;

Fig. 4 is a perspective view showing the controlling device by which the starting and stopping of the advancing mechanism is controlled;

Fig. 5 is a longitudinal vertical section on line 5—5 of Fig. 1, the intermediate portion of the machine being omitted;

Fig. 6 is a partial vertical cross-section on line 6—6 of Fig. 5;

Fig. 7 is a partial vertical cross-section on line 7—7 of Fig. 5; and

Fig. 8 is a side elevation of part of the discharge end of the machine, being in part a longitudinal vertical section on line 8—8 of Fig. 1, and the vertical spraying device being shown partly in section.

Describing now the embodiment of my invention shown in the drawings, it will be seen by reference to Fig. 1 that the machine comprises an elongated casing 9 having an offset portion 10 at one side, the latter forming a paddle wheel compartment, while the main body of the casing forms washing and rinsing compartments, in the usual way. The bottom of these compartments constitutes a tank 11 having two compartments adapted to contain washing and rinsing water respectively, the tank being divided midway of its

length by a transverse partition 12, as indicated by dotted lines in Fig. 1. Toward the end portions of the tank its bottom is preferably inclined upwardly as shown at 13, 14 in Fig. 5. The vertical walls 15, 16 shown in said figure mark the ends of the tank that underlie the paddle wheel compartment 10.

The casing rises above the washing and rinsing compartments high enough to permit the baskets to be moved through the machine over the water in them, and it is open at its ends so that the baskets may be introduced at one end and withdrawn at the other. The casing also encloses the paddle wheel, as shown in Fig. 5, in which the walls 17, 18 constitute the ends of the paddle wheel compartment, and 19 indicates the top thereof.

In the construction illustrated the paddle wheel is in the form of a shaft 20 that extends longitudinally through the paddle wheel compartment and carries a number of paddles or blades 21 secured thereto at intervals along its length and spirally arranged so that they dip successively into the water in the tank as the shaft rotates. This arrangement is indicated by dotted lines in Fig. 1. The shaft 20 is journaled in suitable bearings 22, 23 carried respectively by plates 24, 25 secured to the end walls 17, 18, as shown in Fig. 5. Also secured to said end walls and to the plates 24, 25 by bolts 26 are two brackets 27, 28, that extend longitudinally of the shaft 20 and are provided with vertically disposed end plates 29, 30, respectively, to which are secured cap plates 31, 32. Between the plates 29, 31 are mounted anti-friction bearings 33 which support the shaft 20, and similar anti-friction bearings 34 are mounted between the plates 30, 32, as shown in Fig. 5. Adjacent to the inlet end of the machine the shaft 20 carries a pulley 35 over which runs a belt 36 driven by a motor 37 that is preferably mounted on a stand 38 located above one end of the paddle wheel compartment 10, as best shown in Fig. 1. By this means the shaft 20 is driven from the motor 37, and in the present machine it is intended that when the machine is in use said shaft will be constantly driven.

At its opposite end the shaft 20 is provided with a worm 39, as shown in Fig. 5, the shaft being extended a short distance beyond the worm and being mounted in an anti-friction bearing 40 located between the outer end of the worm and an adjustable plate 41 disposed over the end of the shaft and telescopically fitted on a boss 42 carried by a plate 43 that is secured in position opposite the end of the shaft 20 in the manner hereinafter described. An anti-friction bearing 44, similar to the bearing 40, is mounted between the hub portion 45 of the cap plate 32 and the inner end of the worm 39. An adjustable bolt 46 is mounted in the boss 42 and bears against the outer face of the plate 41, the arrangement

being such that by screwing said bolt in or out the plate 41 may be adjusted longitudinally of the shaft 20 to adjust the ball bearings 40, 44, and also the worm 39, which, as shown in Fig. 6, is connected with the shaft 20 by a key 47 so that it may move longitudinally of the shaft but rotates therewith.

The worm 39 meshes with and drives a worm wheel 48 mounted on and keyed to a transverse shaft 49 journaled in suitable bearings carried by the side walls 50, 51 of a housing 52 which is preferably integral with the plate 32 and encloses the worm wheel 48 and worm 39, as best shown in Fig. 6. The plate 42 is secured to the housing 52, with the boss 42 concentric with the shaft 20, by means of bolts 53, as best shown in Fig. 5. Said plate may therefore readily be removed when desired. A cover plate 54 forms the top of the housing 51, as best shown in Fig. 6.

As best shown in Figs. 1 and 5, the housing 52 lies outside of the casing and adjacent to the forward end of the paddle wheel compartment, and as best shown in Fig. 6 the shaft 49 extends through said housing toward the adjacent side wall 55 of the casing. Mounted on its inner end portion between two collars 56, 57 is a ratchet wheel 58 that is keyed to said shaft so that it rotates therewith. Also mounted on said shaft next to the inner face of said ratchet wheel, is a disc 59 that is loose on the shaft and has secured to its hub portion a sprocket wheel 60. Screws 61 serve to secure the sprocket wheel to said disc. At what is normally the upper portion of the disc 59 it is provided with a peripheral recess 62, best shown in Fig. 3, and, preferably adjacent to said recess, said disc carries a pawl 63 pivotally mounted upon it by means of a pivot pin 64, so that said pawl 63 may swing radially. As shown in Fig. 6, said pawl is located on the outer face of the disc 59 and overlies the teeth of the ratchet wheel 58, so that by swinging said pawl radially it may be moved into or out of engagement with the teeth of said ratchet wheel. The arrangement of these parts is best shown in Fig. 8. A spring 65 tends to move the pawl 63 into engagement with the ratchet wheel, as indicated by dotted lines in said figure. Obviously, when the pawl 63 engages the ratchet wheel, if the ratchet wheel be rotated in a counterclockwise direction as viewed in Fig. 8, the disc 59 will rotate with said ratchet wheel and with the shaft 49, but when the pawl 63 is out of engagement with the ratchet wheel, as shown in full lines in Fig. 8, the ratchet wheel may rotate in that direction independently of said disc.

For normally holding the pawl 63 out of engagement with the ratchet wheel 58 so that the shaft 49 and ratchet wheel may rotate without rotating said disc, a tripping device in the form of a swinging arm 66 is provided, said arm being loosely mounted on the shaft 130

49 adjacent to the outer face of the ratchet wheel 58, as best shown in Figs. 6 and 8. Said arm extends out a short distance beyond the periphery of the ratchet wheel and is beveled 5 at its outer face, as shown at 67 in Fig. 8. A roller 68 mounted on a laterally projecting pin 69 secured to the pawl 63, overlies the trip arm 66 and is adapted to ride on its bevel surface 67. The length of the arm 66 is such that 10 when the roller 68 rides up on said arm the pawl 63 is moved radially out of engagement with the teeth of the ratchet wheel 58, but by moving the trip arm 66 in a clockwise direction as seen in Fig. 8, it will pass out from under the roller 68 and thereby permit the pawl 63 to move inward under the action of the spring 65 into engagement with the teeth of said ratchet wheel.

The normal position of these parts is shown 20 in Fig. 8, at which time the trip arm 66 is substantially vertical and underlies the roller 68 in the recess 62 in the disc 59. Bearing in mind that the shaft 49 and ratchet wheel 58 are constantly rotating, whereas the disc 59 25 and sprocket wheel 60 are stationary, if the trip arm 66 be swung to the right as viewed in Fig. 8, to permit the pawl 63 to engage the ratchet wheel, as soon as such engagement takes place the disc 59 and sprocket wheel 60 30 rotate with the ratchet wheel 58, and the pawl 63 will be, of course, carried around with said disc. When, however, the parts have made a complete rotation the roller 68 will encounter the trip arm 66 and will ride up on its bevel surface 67, thereby moving the pawl 63 35 out of engagement with the ratchet wheel 58 and stopping the rotation of the disc 59. The ratchet wheel will then continue to rotate independently of said disc. Whenever, therefore, the disc 59 is set in motion it will make a 40 single complete rotation and then stop. The function of this mechanism is to advance the baskets through the machine a distance corresponding to that measured by a single rotation 45 of the sprocket wheel 60 each time the trip arm 66 is actuated, so that the baskets will move intermittently through the machine. The intervals during which the baskets remain stationary may, of course, be controlled 50 by appropriately actuating the trip arm 66.

Rotation of the sprocket wheel 60 is made effective to move the baskets through the machine in the following manner: An endless chain 70 extends longitudinally through the 55 machine with its upper flight above the level of the water in the tank, said chain being supported at its ends by sprocket wheels 71, 72 mounted on transverse shafts 73, 74, as best shown in Fig. 5. The shaft 74 is mounted in 60 suitable bearings in the casing of the machine and is driven from the sprocket wheel 60 by a chain 75 that runs over the latter sprocket wheel and over a sprocket wheel 76 mounted on and keyed to the shaft 74, as shown in 65 the latter figure. The shaft 73 is preferably

mounted in bearing blocks 77 adjustable longitudinally of the machine so that the tension of the conveyor may be adjusted.

As shown in Fig. 6, the conveyor 70 is supported at its margins by channel shaped 70 tracks 78 placed near the opposite side walls of the washing and rinsing compartments, in position to receive the longitudinally extending members or chains that form the side portions of said conveyor. The side members of 75 the conveyor rise a short distance above the side margins of the tracks 78 so that they are adapted to support baskets 79 which rest on the conveyor and are carried along by it as it travels through frictional engagement therewith. In prior constructions it has been customary to provide the conveyor with lugs or equivalent devices to positively engage the baskets and move them along through the machine, but such construction is objectionable 80 because it sometimes happens that some obstacle prevents the outgoing basket from leaving the conveyor, in which case if the conveyor continues to move breakage is likely to follow. By depending only on frictional engagement between the baskets and the conveyor for advancing them through the machine there is no danger of damage from any such cause.

Since the sprocket wheel 60 is normally 85 stationary the conveyor chain is also normally stationary, but said sprocket wheel and the conveyor may be set in motion by tripping the arm 66 as has been described. This may be done by a separate manual operation, 90 but it is desirable that the conveyor be automatically started as soon as a fresh basket is placed in position on it, and I have provided mechanism for that purpose. By reference to Fig. 1, it will be seen that a lever 100 or trigger 80 is pivotally mounted to swing in a horizontal plane in such position that it projects into the path of the baskets, said lever being mounted on the lower end of a vertically disposed rock shaft 81 provided 105 with a spring 82 which tends to return the lever 80 to its normal position at right angles to the path of the baskets. A suitable stop 83 limits the movement of said lever 110 under the influence of said spring and stops it when it is restored to its normal position. The upper end of the rock shaft 81, which is journaled in a bearing 84, as shown in Fig. 5, is provided with a crank 85, which is connected by a connecting rod 86 with a crank 87 carried by a similar rock shaft 88 at the opposite end of the machine. As best shown in Fig. 8, the latter rock shaft has an arm 89 at its lower end which engages a slot 90 in one end portion of an actuating bar 91, the 115 opposite end of which is connected by a pivot 92 to the trip arm 66. The arrangement is such that when a basket engages and actuates the lever 80 it rocks the rock shaft 81 and through the connecting rod 86 also 120

rocks the rock shaft 88 in such direction as to move the actuating bar 91 to the right as viewed in Fig. 8. This moves the trip arm 66 out from under the roller 68, thereby permitting the pawl 63 to engage the ratchet wheel 58; consequently the disc 59 and sprocket wheel 66 rotate, thereby advancing the conveyor until the sprocket wheel 60 has made a complete rotation, whereupon it 10 stops. The lever 80 is so located that when the operator places a basket on the inlet end of the conveyor it actuates said lever and sets the conveyor in motion, but if desired it would be quite practicable to operate the 13 lever 80 by hand if that way of starting the conveyor were preferred.

The advancement of a basket from the inlet end of the machine during the periodic movement of the conveyor makes way for the 20 application of another basket to it, and in this way a succession of baskets may be introduced into and delivered from the machine. In their movement past the paddle wheel the 25 contents of the baskets are first washed by water from the washing compartment and then rinsed by water from the rinsing compartment. After the washing and rinsing has been done it is desirable that the dishes or other articles be sprayed as they leave the 30 machine, not only to further cleanse them, but also to dry them. This spraying is done with very hot water which evaporates instantly and leaves the articles dry. For the purpose of effecting this spraying automatically, and 35 only at such times as a basket is moving out of the machine, so that there will be no wastage of the hot water used for that purpose, I provide spraying means controlled by the rotation of the disc 59. As shown in Fig. 7, 40 a transversely disposed pipe 93 is mounted at the outlet end of the casing over the path of the baskets, said pipe being provided with perforations 94 in its under side so that it discharges spray water downwardly upon the 45 contents of the baskets. I also provide a vertically disposed spray pipe 95 at one side of the path of the baskets, said pipe being provided with lateral openings 96 arranged to discharge spray water laterally upon the 50 contents of the baskets. These two pipes are connected by pipes 97, 98 and a T-coupling 99, with a pipe 100 that is connected with a hot water supply pipe 101, as shown in Figs. 5 and 8. The pipe 100 is provided with a quick 55 acting valve 102, such as a whistle valve, which valve has a downwardly projecting stem 103, as best shown in Fig. 8. A plunger 104 having a head 105 that engages the valve 60 stem 103 is mounted in an upright position under said stem and is pivotally supported at 106 by means of a link 107 pivotally connected at 108 with one of the walls of the casing. At its lower end the plunger 104 carries a roller 109 that is adapted to rest in 65 the recess 62 when the disc 59 is in its normal

position, and to ride on the periphery of said disc as the latter rotates. At its upper end the plunger 104 is provided with a vertical slot 110 into which extends a guide pin 111 carried by a bracket 112 secured to the valve 70 102 and depending therefrom. By this arrangement the plunger 104 is held in proper position and is free to move upward to actuate the valve stem 103 to open the valve and permit the discharge of spray water. This 75 occurs whenever the disc 59 begins to rotate, since the roller 109 then rides up on the periphery of said disc, thereby moving the plunger 104 upward and opening the valve 102. As soon as the disc completes its rotation the roller 109 drops into the recess 62 80 and the spray valve automatically closes. The plunger 104 serves also to center the disc 59 in its normal position after it has completed its rotation, owing to the fact that the 85 curvature of the recess 62 corresponds substantially to that of the roller 109.

Obviously since the disc 59 rotates only while the conveyor is moving to advance the 90 baskets through and discharge them from the machine the spraying mechanism will operate only to spray the outgoing basket, after which it will stop until the next basket is being discharged.

The operation of the machine has already 95 been quite fully explained, and, therefore, it is not thought necessary to restate it. It will be seen that the ratchet wheel 58 and disc 59 with the pawl 63 constitute optionally controlled intermittently operating clutch 100 mechanism by which the conveyor is driven to a predetermined extent each time the tripping device is actuated to operatively connect 105 said clutch members, said tripping device being restored to its normal position immediately after it has been actuated by the spring 82. By the construction described the disc 59 makes a complete rotation before stopping, but obviously provision could readily be made so that the clutch members would be 110 disengaged after less than a complete rotation of said disc.

It will be apparent to those skilled in the art that the mechanism by which I accomplish the stated objects of my invention may 115 be modified in many particulars, and I wish it to be understood that the claims herein-after made are not intended to be limited to the specific construction shown and described except in so far as special features of such construction are particularly claimed.

What I claim as my invention and desire to secure by Letters Patent, is—

1. A washing machine comprising washing 125 means, conveyor means operable to move the articles to be washed past said washing means, clutch mechanism for driving said conveyor means from said driving means, including a constantly driven clutch member and a normally stationary clutch member 130

- adapted to be connected therewith, one of said clutch members being in the form of a ratchet wheel and the other clutch member having a pawl adapted to engage said ratchet wheel, a tripping device for moving said pawl out of engagement with said ratchet wheel when said clutch members are rotated in unison to a predetermined extent, and means operable to actuate said tripping device to permit said pawl to engage said ratchet wheel.
2. A washing machine comprising washing means, conveyor means operable to move baskets containing the articles to be washed past said washing means, continuously operating driving means, intermittently operating means for driving said conveyor means from said driving means, and means actuated by the introduction of a basket into the machine for starting said conveyor means.
3. A washing machine comprising washing means, conveyor means operable to move baskets containing the articles to be washed past said washing means, continuously operating driving means, intermittently operating clutch mechanism for driving said conveyor means from said driving means, and means actuated by the introduction of a basket into the machine for actuating said clutch mechanism to connect said conveyor means with said driving means.
4. A washing machine comprising washing means, conveyor means operable to move baskets containing the articles to be washed past said washing means, continuously operating driving means, intermittently operating clutch mechanism for driving said conveyor means from said driving means, a trip device for actuating said clutch mechanism to disconnect said conveyor means from said driving means, and means operable by the introduction of a basket into the machine for moving said trip device out of operative position.
5. A washing machine comprising washing means, conveyor means operable to move the articles to be washed past said washing means, spraying means adjacent to the outlet end of the machine, including a normally closed valve, continuously operating driving means, and intermittently operating means for driving said conveyor means from said driving means and for temporarily opening said valve.
6. A washing machine comprising washing means, normally stationary conveyor means adapted to be actuated to move the articles to be washed past said washing means, spraying means adjacent to the outlet end of the machine, and means for actuating said conveyor means to a predetermined extent and contemporaneously opening said valve, said actuating means being controlled automatically, or by hand, optionally.
7. A washing machine comprising washing means, an endless conveyor operable to move the articles to be washed past said washing means, continuously operating driving means, a ratchet wheel driven by said driving means, a rotating disc connected with said conveyor for driving the same, a pawl carried by said disc and adapted to engage said ratchet wheel for connecting said disc therewith, a trip device normally holding said pawl out of engagement with said ratchet wheel and movable to permit it to engage the same, and means operable to actuate said trip device to release said pawl.
8. A washing machine comprising washing means, an endless conveyor operable to move the articles to be washed past said washing means, continuously operating driving means, a ratchet wheel driven by said driving means, a rotating disc connected with said conveyor for driving the same, a pawl carried by said disc and adapted to engage said ratchet wheel for connecting said disc therewith, a trip device normally holding said pawl out of engagement with said ratchet wheel and movable to permit it to engage the same, means operable to actuate said trip device to release said pawl, spraying means adjacent to the outlet end of the machine, including a normally closed valve, and means operated by the rotation of said disc for opening said valve.
9. A washing machine comprising washing means, an endless chain conveyor adapted to support and frictionally engage baskets containing the articles to be washed and move them past said washing means, continuously operating driving means, and intermittently operating means for driving said conveyor from said driving means, said operating means being controlled automatically, or by hand, optionally.
10. A washing machine comprising washing means, a conveyor adapted to support and frictionally engage baskets containing the articles to be washed and move them past said washing means, baskets seating upon said conveyor, conveyor operating means, and means controlling the operation of said operating means, said controlling means including a trigger extending into the path of the entering basket, the baskets being free from the conveyor except for the frictional contact between the conveyor and said baskets.

GEORGE P. ANSTISS.
